[57] CLAIM

The ornamental design for a visor for pickup trucks, as shown and described.

DESCRIPTION

FIG. 1 is a perspective view of a visor for pickup trucks showing my new design in mounted position on a pickup truck which is fragmentarily shown in broken lines for illustrative purposes only and forms no part of the claimed design;

FIG. 2 is an enlarged top plan view thereof;

FIG. 3 is a front elevation view of FIG. 2;

FIG. 4 is an enlarged side elevation view of FIG. 2;

FIG. 5 is a bottom plan view of FIG. 2;

FIG. 6 is a rear elevation view of FIG. 2; and

FIG. 7 is an enlarged cross-sectional view of FIG. 2 taken along line 7—7 therein.

FIG. 1***FIG. 2******FIG. 3***

FIG. 4***FIG. 5******FIG. 6******FIG. 7***
